The ornamental design for a decorative light holder, as shown and described.

DESCRIPTION

FIG. 1 is a top plan view of my design for a decorative light holder;

FIG. 2 is a bottom view thereof;

FIG. 3 is a front view thereof;

FIG. 4 is a rear view thereof;

FIG. 5 is a right side view thereof;

FIG. 6 is a right side view of my design when the structure is in a folded, assembled condition; and,

FIG. 7 is a perspective view of the folded, assembled device.

*Fig.1.**Fig.2.**Fig.3.**Fig.4.**Fig.5.**Fig.7.*
